[57] CLAIM

The ornamental design of a vacuum bottle, as shown and described.

DESCRIPTION

FIG. 1 is a perspective view of the vacuum bottle taken from above and to one side of the vacuum bottle;

FIG. 2 is a side elevation of the vacuum bottle;

FIG. 3 is a side elevation of the vacuum bottle taken from the right of FIG. 2, it being understood that a view of the vacuum bottle taken from the left of FIG. 2 is a mirror image of this FIG. 3;

FIG. 4 is another side elevation of the vacuum bottle taken from the left of FIG. 2;

FIG. 5 is a top plan view of the vacuum bottle; and,

FIG. 6 is a bottom plan view of the vacuum bottle.
